CLAIM

The ornamental design for a tarp anchor, as shown and described.

DESCRIPTION

FIG. 1 is a top perspective view of a tarp anchor;
FIG. 2 is a front view of FIG. 1;
FIG. 3 is a rear view of FIG. 1;
FIG. 4 is a first side view of FIG. 1;
FIG. 5 is a second side view of FIG. 1;
FIG. 6 is a top view of FIG. 1; and,
FIG. 7 is a bottom view of FIG. 1.
The broken lines depict portions of the article that form no part of the claimed design.
